UNITED STATES PATENT OFFICE.

FREDERICK K. VREELAND, OF MONTCLAIR, NEW JERSEY, ASSIGNOR TO VREELAND APPARATUS COMPANY, OF NEW YORK, N. Y., A CORPORATION OF NEW YORK.

METHOD OF PRODUCING ANALGESIA.

1,257,555.

Specification of Letters Patent. Patented Feb. 26, 1918.

Application filed June 25, 1914. Serial No. 847,199.

To all whom it may concern:

Be it known that I, FREDERICK K. VREELAND, a citizen of the United States, residing at Montclair, in the county of Essex and 5 State of New Jersey, have invented a certain new and useful Method of Producing Analgesia, of which the following is a specification.

My invention relates to the production of 10 anesthesia or analgesia by means of electric currents, and while it has been especially developed for the production of analgesia in the teeth, so that they may be operated upon without pain to the patient, it is capable of 15 effective use for producing analgesia for other surgical work.

It is well known that under favorable conditions a suitable electrical current may produce analgesia or render the bodily tissues 20 insensitive to pain. Heretofore, however, any practical attempts to produce analgesia by means of electric current have been limited in scope, and in most cases altogether impracticable, because the currents used 25 were not suitable for the purpose and the method of applying the current was faulty or inadequate. For these reasons the eradication of pain by the application of electric currents has not been heretofore completely 30 realized, and in fact the current itself often has been a source of pain. In the practice of the present invention the sensitiveness of the nerves and tissues to pain is completely eliminated when the current is used, and its 35 modes of application are of such a character that it may be applied even to the most excessively sensitive tissues of teeth without discomfort to the patient.

In order that the invention may be better 40 understood attention is directed to the accompanying drawings, forming part of this specification, and in which,

Figures 1, 2 and 3 show the wave form of current used;

Fig. 4 is a diagram showing the circuit connections of the preferred arrangement for generating, controlling and applying the current;

Figs. 5 and 6 illustrate devices for applying the current exteriorly to the principal dental nerves; and

Figs. 7, 8 and 9 are detail views showing various devices for applying the current to individual teeth.

The current that I prefer to employ is a 55 high frequency sinusoidal current of practically constant amplitude. This current may be a pure alternating current, as shown in Fig. 1, or a unidirectional pulsating current, as shown in Fig. 2, or a reversing pulsating current, as shown in Fig. 3. The current wave forms shown in Figs. 2 and 3 may be considered as a result of superimposing a pure alternating current upon a direct current. All three wave forms are effective, but 60 for convenience I prefer usually to employ the simple alternating current of pure sine wave form, shown in Fig. 1. The character and frequency of the current used to produce anesthesia or analgesia are highly important, as I have determined by actual demonstration. If the current is not suitable or is not correctly applied, the analgesia will not be complete, or the current itself will produce discomfort, or both. For 65 example, if a direct current of moderate intensity is suddenly applied to the body it produces a twinge at the moment of application, which sensation quickly passes away, since the nerves involved apparently accommodate themselves to the current. If such a current is gradually applied it gives no sensation, but any sudden increase is felt unpleasantly. In either case analgesia is not 70 produced. Periodically repeated applications of such a current produce a painful 75 succession of twinges, or if the applications are rapid, a practically continuous pain. If this rapidity of the applications is sufficient, some analgesia may be produced. A sinusoidal alternating current of the same maximum intensity and applied with the same 80 frequency as in the last example referred to (i. e. the same number of alternations or impulses per second) produces a less painful 85 effect than the intermittent direct current, but with ordinary frequencies the shock of successive impulses is very unpleasant, and under some conditions extremely painful. As the frequency of the alternating current 90 increases, the shock gradually diminishes, and finally disappears. By applying a high 95 frequency sinusoidal current of the character and in the manner herein set forth, the full analgesic effect is produced without painful effect of the current itself, even when applied to the most sensitive tissues. Sinusoidal currents have been used hereto-

fore for therapeutic purposes, but the frequencies employed have been low, usually no more than from 10 to 60 cycles per second. It is well known that such currents of low frequency when applied to the bodily tissues or nerves produce a disagreeable or painful sensation of shock. The sensation is greater and more unpleasant than in the case of a direct current of the same intensity, because of the repetition of the successive current impulses. As the frequency is increased, it is found that the successive impulses are not so distinctly felt, and the sensation of the current is milder and less painful.

If the frequency is sufficiently high and the mode of application is suitable, the nerves are incapable of responding to the successive impulses, and the sensation of shock is completely eliminated. If such a current of suitable magnitude is applied to a nerve by suitable means it apparently has the effect of inhibiting the power of the nerve to transmit the sensation of pain, and hence the tissues which the nerve controls may be cut or otherwise operated upon without discomfort to the patient, and sometimes without actual consciousness of the fact. Usually, however, the sensation of touch is not completely eliminated, and hence the effect is perhaps more accurately described as an analgesia or absence of pain, rather than an anesthesia or absence of sensation.

The current itself, when properly applied, does not produce painful or disagreeable sensations. In many cases, particularly of dental work, it has been observed that the patient is sometimes conscious of a numbness of the tissues affected; in other cases there is apparently a sensation of slight warmth, and in others a slight cooling sensation, but there has been an entire absence of the shock or painful effect that has accompanied previous attempts at electric anesthesia. It is highly important that the amplitude of the current be kept relatively uniform, since any irregularities or sudden fluctuations of the current are objectionable and cause discomfort to the patient. All necessary changes in the current strength or amplitude should be made gradually. It is also important that the current shall have a high frequency, and in practice I prefer to employ a frequency of between 1,000 and 2,000 cycles per second. Satisfactory analgesia may be obtained with lower frequencies, but as the frequency is diminished the sensation of the current increases. On the other hand, good results may be secured by the use of higher frequencies, but for convenience in generating and handling the current, I prefer not to exceed the limit named.

Another feature of the current employed is its pure sine wave form. The smooth and

gradual undulations of the current avoid the shock or disagreeable sensation which results from any sudden variation of the current.

It should be understood that in describing the current as a high frequency sinusoidal current I am not contemplating the excessive frequencies sometimes used for therapeutic purposes when employing a spark oscillator of the Tesla or Oudin type. Such currents may have a frequency of a million or more cycles per second, or in other words 500 times the frequency that I employ; they are not continuous, but intermittent; the wave form is not sinusoidal; the oscillations are not of constant amplitude, but are strongly damped, and they produce no anesthetic effect. For generating the high frequency sinusoidal currents of constant amplitude, I prefer to employ the sine wave oscillator described in my United States Patents Nos. 829,447 and 829,934 dated August 28, 1906. Such an apparatus is shown diagrammatically in Fig. 4. The high frequency sinusoidal currents are set up in an oscillating circuit 1-2-1, including the field coils 1-1 and condenser L. A secondary coil 3 is mounted in inductive relation to one or both of the field coils 1-1, and the electromotive force thus induced in the secondary coil is employed to set up the current applied to the patient. The secondary coil 3 may be and preferably is movable with respect to the field coils 1, 1 for the purpose of adjusting the electromotive force.

In series with the coil 3 is an adjustable rheostat or equivalent impedance 4 which controls the intensity of the secondary circuit. The secondary circuit is completed through electrodes 5, 6 by which the current is applied to the patient's body. A switch 7 is shown in the secondary circuit.

The arrangement shown in Fig. 4 is not the only one which may be employed, and in fact any suitable arrangement may be used by which sinusoidal currents of the necessary high frequency and practically constant amplitude may be generated. Furthermore, it will be obvious that suitable means for controlling the current may be substituted for the movable coil 3 and rheostat 4. In applying the current to the patient the usual procedure is as follows:

One or more electrodes 5 are applied to the nerve or other portion of the patient's body to be treated, and another electrode 6 is applied to some convenient portion of the body, for instance, the patient's hand, so as to form a circuit through the body involving the nerve or territory to be treated. In some cases instead of using one neutral electrode 6, both electrodes are applied to the nerve or nerves to be treated. The rheostat 4 is set to a high resistance and the electromotive force is applied to the patient by

closing the switch 7 or by moving the coil 3 into inductive relation with the coils 1, 1. The maximum resistance of the rheostat 4 should be so chosen with relation to the electromotive force induced in the coil 3 that the current flowing through the patient is not sufficient to produce an unpleasant sensation at the moment of completing the circuit. The current is then gradually increased by cutting out resistance 4 or increasing the electro-motive force in coil 3, or both, until the desired analgesia is produced. It is desirable to increase the current intensity gradually, since any sudden variation or irregularity may produce an unpleasant sensation. When the current is applied gradually the patient experiences no discomfort and may in fact be entirely unconscious of the current, even when it has reached the magnitude required for complete analgesia. The application of current to the patient is continued as long as analgesia is required. When the current is shut off the normal functions of the nerves and sensitivity of the tissues return almost immediately. If analgesia is required for a considerable length of time it may be necessary to increase the intensity of the current from time to time as the nerves begin to accustom themselves to the current. This may be accomplished by cutting out further resistance in the rheostat 4 when required.

In order to reduce any fluctuations in the current applied to the patient due to variations of the contact resistance at the electrodes, or to other causes, it is desirable to make the resistance 4 large with respect to the resistance of the external circuit. The electromotive force induced in the coil 3 should be correspondingly large, so that the greater part of the electromotive force will be consumed in the resistance 4 and the relatively smaller remainder applied to the patient. The apparatus then operates practically as a constant current device, and accidental fluctuations of the current, which might cause discomfort to the patient, are avoided. The resistance of the patient's body, including the contact resistance at the electrodes, is usually between 1000 and 10,000 ohms. It is desirable therefore that the rheostat 4 should have a maximum resistance of from 50,000 to several hundred thousand ohms, and its range of adjustment should be such that when the maximum current is flowing its resistance is still large compared with the resistance of the external circuit.

The mode of application of the current to the patient may be varied to suit the requirements of the case, and successful results to a certain extent will depend upon the ingenuity and resourcefulness of the operator in applying the electrodes in such

a way as to secure the maximum effect. Where general anesthesia is required the electrodes should be so applied that the current traverses the brain or some portion of the spinal cord. For producing local anesthesia or analgesia in a restricted portion of the body it is sufficient to apply the current to the sensory nerve or nerves to be anesthetized. I prefer to apply the active electrode or electrodes 5, at some point where the nerve or nerves lie close to the surface, in such a manner that the current when entering the body will traverse the nerve tissue, thus inhibiting its function of transmitting the sensation of pain. The electrode 6 through which the circuit is completed may be neutral and applied to the body at some convenient point, or it also may be active and applied in the neighborhood of a nerve or nerve trunk. Where a multiplicity of electrodes 5 are employed each one should have a separate resistance or equivalent impedance 4 to insure a proper distribution of the current. In general it is desirable that the active electrodes 5 be small to concentrate the current at the desired point, while the neutral electrode, when used, is made relatively large, to distribute and reduce the concentration of the current. The analgesic effect depends upon the concentration of the current in the nerve tissue rather than on its aggregate amount. Where the region to be anesthetized is controlled by a plurality of nerves, or nerve trunks, a plurality of electrodes 5 or 6 are employed, each applied to its respective nerve or nerve trunk at an appropriate point between the region to be treated and the brain or spinal cord.

Where the invention is used to produce analgesia in the teeth the current should be applied to some portion of the dental nerve or nerves supplying the tooth or teeth to be operated upon. It is possible to anesthetize a number of teeth simultaneously, by applying an electrode to the nerve at some distance from the teeth. There are several places at which such electrodes may properly be applied. The two halves of the lower jaw are supplied respectively by the right and left inferior maxillary nerves. Each of these nerves approaches the outer surface of the chin at the point where it passes through the mental foramen. A small electrode applied immediately over the mental foramen on either side will lead the current to the nerve and anesthetize the corresponding teeth on the lower jaw. In Fig. 5 I show an arrangement of the electrodes 5 and supporting harness 8 for applying electrodes to both the mental foramina.

The teeth of the upper jaw are supplied by the two superior maxillary nerves, which penetrate the skull respectively through the

right and left infraorbital foramen, which are located at opposite sides of the nose below the eye. Electrodes applied at one or both of these points will control the teeth 5 of the upper jaw; and in Fig. 6 I show an arrangement of electrodes for this purpose.

The dental nerves may also be reached from points in the back of the mouth. It is usually preferable, however, to apply the 10 current at the external points above mentioned.

I have found in practice that under ordinary conditions greater convenience is secured when the current is applied only to 15 the particular tooth which is to be operated upon. To this end an electrode may be applied to the surface of the gum near the root of the tooth, on either the outside or the inside of the jaw. Or, two electrodes may be 20 employed, one on the outside and one on the inside, so that the current passes from one to the other through the jaw tissue and thus traverses the nerve supplying the tooth. Such electrodes may be held in place by 25 rubber suction cups 9, one of which is shown in Fig. 7, or they may be supported from a clamp attached to an adjacent tooth and supporting an adjustable arm carrying at its extremity an electrode, as shown in Fig. 8.

30 The best results, however, are obtained when the current is applied directly to the tissue of the tooth, and it may be successfully applied in several different ways. A convenient method is to spring a metallic 35 clamp over the tooth near the gum and attach a conducting wire to this clamp, which serves as an electrode. The clamp should be insulated except where it touches the tooth, by suitable insulating covering or by 40 a rubber dam stretched over the tooth between the clamp and the gum.

The clamp used may be one well known to dentists, consisting of a pair of jaws connected by a stiff spring. Such an electrode, 45 however, is sometimes objectionable because of the rigidity of the jaws, and unless the jaws are accurately fitted to the teeth they may make contact at only four points. The current will then be concentrated at these 50 four points, and the current density in the tooth tissue may thus become so high as to cause pain or discomfort to the patient before the current is strong enough to completely inhibit the functions of the nerve.

55 To avoid this difficulty I employ an electrode of the form shown in Fig. 9, in which the jaws which embrace the tooth are in the form of elastic forks between the points of which fine wires are stretched like bow 60 strings. Such an electrode will adapt itself to the contour of the tooth and will establish a good contact of sufficient area to prevent undue concentration of the current.

It is sometimes inconvenient to apply an

electrode at the base of the tooth. Under 6 such circumstances the electrode may be applied at any desired portion of the tooth surface. The electrode for this purpose may consist of a mass of conducting cement stuck to the tooth surface, or an adjustable electrode 70 may be employed, such as that shown in Fig. 8. The electrode proper consists in a mass of wet cotton, or other conducting material, contained in a cup of soft rubber or other insulating material and connected 75 to a wire or conducting lead. This cup is supported by a double-jointed arm, having pivots allowing it to move in any direction in a given plane. The supporting arm is made of spring metal or other elastic material to hold the electrode in firm contact with the tooth. The end pivot of the supporting arm is carried by a saddle, which is fixed adjustably to the bow of a clamp adapted to be sprung over the tooth. The 80 saddle is arranged to be adjustable at any point of the bow so as to permit angular adjustment of the saddle and the arm which it carries. The clamp is applied to a tooth adjacent or near to the one to be operated 85 upon, and the electrode cup is capable of adjustment to make contact at any desired point of the tooth surface. I prefer to construct the supporting arm wholly or in part 90 of insulating material, so that ample creeping space may be provided to prevent surface leakage of the current.

Whatever mode of attachment is employed for the electrode 5, the return electrode 6 may be applied to any convenient 100 portion of the patient's body, being grasped for example in the patient's hand or being applied as a plate or pad to the patient's cheek. Preferably for dental work this electrode 6 is a small metal disk slipped into 105 the patient's mouth. Such an electrode, by making contact with the moist mucous membrane, eliminates to a large extent the skin contact resistance.

Having now described my invention, what 110 I claim as new and desire to secure by Letters Patent, is:

1. The method of producing complete or partial anesthesia or analgesia which consists in subjecting the nerve, or nerve center 115 or tissues controlled thereby, to the effect of electric current of high frequency and substantially uniform amplitude, as set forth.

2. The method of producing complete or partial anesthesia or analgesia which consists in subjecting the nerve, or nerve center or tissues controlled thereby, to a current 120 having the form of a sine wave of high frequency and substantially uniform amplitude, as set forth.

3. The method of producing complete or partial anesthesia or analgesia which consists in subjecting the nerve, or nerve center

or tissues controlled thereby, to a current having a frequency in excess of 1000 cycles per second, and of substantially uniform amplitude, as set forth.

5. 4. The method of producing complete or partial anesthesia or analgesia which consists in subjecting the nerve, or nerve center or tissues controlled thereby, to the effect of electric current of high frequency and sub-

stantially uniform amplitude, the current being gradually increased in amplitude until the desired effect is secured, as set forth.

This specification signed and witnessed this twenty-second day of June, 1914.

FREDERICK K. VREELAND.
